DISPENSING DEVICE FOR HAIRPINS AND
THE LIKE

Sam Katz, Brooklyn, N. Y.

Application January 25, 1938, Serial No. 186,756

6 Claims. (Cl. 312—67)

The object of this invention is to provide a dispensing device, more particularly adapted for use in beauty parlors, and which may be mounted upon a stand or the back of a chair occupied by a woman during a hair dressing operation, as for example, "finger waving", so that the hairdresser may conveniently and quickly be supplied with each of the relatively large number of hairpins required to hold the strands or curls of hair in place during the drying and setting thereof.

In the operation of my device the pins are successively presented exterior of a holding casing therefor, by automatic action effected by the withdrawal of hairpins for use by the operator. The hairpins may initially be held together in stack formation similar to a stack of wire staples used in a stapling machine of well known character.

The invention will be described with reference to the accompanying drawing, in which

Figure 1 is a side elevation, partly broken away, of an embodiment of the invention, an initial hairpin having been advanced for finger removal.

Figure 2 is a schematic plan view of a chair showing two of my devices mounted on the back thereof.

Figure 3 is a front elevation, of the embodiment shown on Figure 1.

Figure 4 is a fragmentary view of the lower portion of the structure shown in Figure 1 showing the portion of the parts after finger removal of a hairpin from its position in Figure 1.

Figure 5 is an enlarged view of the structure shown in Figure 4 with the ejector mechanism in position for action upon a pin underlying an overlying pin which is in position for finger removal.

Figure 6 is a horizontal section on the line 6—6 Figure 5.

Figure 7 is a perspective view of the ejector element.

Referring to the drawing, I have shown at 1 a metallic casing, which may conveniently be made in rectangular form, and having a width, thickness and length sufficient to enclose, and form guiding walls for, a stack of hairpins shown at 2. The casing may be closed at its top by a removable cover 3, and to removably hold the cover in position the casing at its front and rear walls, or elsewhere, may be formed with detents as at 4 Figure 1 to be received within sockets such as 5 formed in the cover member.

Within the casing and movable upwardly and downwardly therein is positioned a carrier 6 for the ejector mechanism.

The carrier comprises a trough member having vertical narrow side flanges, each flange being formed with a cam-slot at 6x. Received within each cam-slot 6x are the horizontal rounded extensions 7x of a set of arms 7, each set of arms 7 being carried at one side of an ejector slide 8. The ejector slide is normally maintained in the position shown in Figures 1, 5 and 6 by means of a spring 9 one end of the spring being carried by the slide and the other end being secured to the carrier 6.

At this rear end slide 8 is formed with an upwardly and inwardly bent hook 8x. The opposite end of the slide carrying an upwardly bent lip 8xx. Centrally thereof the slide carries arms 10, each arm projecting laterally beyond an appropriate side wall of the casing 1 which is cut away at 11 for this purpose. Thus arms 10 may receive pressure from the fingers of an operator for bodily moving the slide to the position shown in Figure 4.

Between the bottom wall of the casing and the carrier 6 is placed a spring 13 by means of which the carrier and its connected parts are gradually moved upward within the casing as the hairpins are ejected through an opening at 1x in 25 the front wall of the casing.

It will be understood that if desired, the carrier may be held against bodily movement and the spring, if a spring is required, may be placed above the stack of hairpins so that as 30 the bottom hairpins of the stack are ejected the stack will gradually move downward. The present arrangement, however, enables more ready insertion of a fresh stack of hairpins.

In the operation of the device, a stack of hairpins is inserted into the casing, the cover being removed for that purpose, and then being returned to closing position. Such insertion will cause depression of the carrier against the tension of spring 13, the parts assuming the position shown in Figure 1, except that the pin therein shown as projected outwardly will still be in its original position in the stack, not projected, and hook 8x will be slightly back of its position shown in Figures 1, 5 and 6, its point 35 being in line with the line of division between the lowermost hairpin head and the head of the hairpin immediately above it. The operator will then, by means of arms 10, move the slide to the right thereby causing the hook 8x to separate the 40 lowermost hairpin from the stack and project it to the position shown in Figure 1.

At the end of the operation just described the slide is released and spring 9 will return it to initial position. From this point the projection 55

of each one of the stack of hairpins will be automatically effected by the manual removal of the initially projected hairpin and the succeeding ones. This follows because upwardly projected 5 lip 8xx of the slide will lie immediately forward of the head of the projected hairpin. When the pin is moved outwardly by the fingers of the operator, the slide will likewise be moved, to cause hook 8x to project the overlying pin. This projecting movement will continue until the front 10 one of each of the two sets of arm extensions 7x of the slide is carried down the inclined section of the appropriate cam-slot 6x. Lip 8xx is thereby caused to release the hairpin, which is then 15 completely ejected by the manual movement. The release of the slide in such manner enables spring 9 to return it to the position of Figures 1, 5 and 6.

In Figure 2 I have shown a plan view of a chair, 20 two of the devices being shown mounted face to face upon the back of the chair.

Having described my invention, what I claim and desire to secure by Letters Patent is as follows:

25 1. A dispensing device for hairpins, comprising a casing having supporting walls for a stack of hairpins contained therein, one of said walls being provided with a dispensing opening, a carrier within the casing, a slide ejector movable within 30 the casing and operatively connected to the carrier, said ejector being formed with a hooked end to engage a hairpin at the end of the stack distant from said opening, means on said ejector projecting exteriorly of the casing whereby the 35 ejector may be manually moved to propel a hairpin through said dispensing opening, and a lip carried by the ejector and spaced from the hooked end of the latter, said lip adapted to be engaged by the hairpin so projected upon a return movement of the ejector, whereby the hairpin is 40 adapted to actuate the ejector when the hairpin is grasped by an operator and moved outwardly of the casing.

45 2. A dispensing device for hairpins, comprising a casing having supporting walls for a stack of hairpins contained therein and having a dispensing opening in one of said walls, a slide ejector within the casing and movable relatively to the stack, a fingerpiece connected to the ejector 50 and projected exteriorly of the casing whereby the ejector may be moved in a direction away from the casing, said ejector being formed with a hook at one end to engage a hairpin at the end of the stack, the ejector being formed with 55 a lip at its opposite end, said lip being adapted to be engaged by a hairpin upon a movement of the ejector inwardly of the casing, whereby the hairpin is adapted to actuate the ejector when the hairpin is grasped by an operator and moved 60 outwardly of the casing.

65 3. A dispensing device for hairpins, comprising a casing having supporting walls for a stack of

hairpins contained therein, a dispensing opening being formed in one of said walls, a carrier within the casing and formed with a cam slot, a slide ejector having an element projected within said cam slot, said ejector being formed at one end with a hook adapted to engage a hairpin at one end of the stack, the ejector carrying a lip at its opposite end, a spring carried by the casing and engaging the ejector, the ejector having an extension projecting exteriorly of the casing 10 enabling bodily movement of the ejector to cause its hook to engage and project said hairpin through the dispensing opening, the spring being adapted to return the ejector to inactive position, the ejector in its return movement bringing said 15 lip into engagement with the projected hairpin, whereby the hairpin in an additional movement imparted to it in a direction away from the casing will actuate the ejector.

4. A device constructed in accordance with 20 claim 3, in which the cam slot is so formed as to withdraw the lip end of the ejector from the hairpin toward the end of the active movement of the ejector in a direction away from the casing.

25 5. In dispensing devices for hairpins, a casing adapted to receive a stack of hairpins, said casing being formed with a dispensing opening, an ejector within the casing and having a fingerpiece projected beyond the casing, said ejector 30 comprising a member formed at each end with an angularly bent extension, each extension being adapted to abut the rounded end of a U-shaped hairpin, a cam engaging element carried by the ejector, and a cam device adapted to act upon 35 said cam engaging element to effect a tilting movement of the ejector when the latter is given bodily movement relatively to the cam device, whereby said tilting movement carries the ejector out of engagement with the hairpin.

40 6. A dispensing device for hairpins, comprising a casing having supporting walls for a stack of hairpins contained therein, a carrier within the casing, a spring engaging the casing and the carrier and adapted to maintain the latter in engagement with said stack, a cam on the carrier, 45 an ejector movable relatively to the carrier and having a cam engaging element adapted to engage said cam, the ejector being formed at each end with an extension adapted to engage the rounded end of a U-shaped hairpin, a spring 50 carried by the casing and adapted to hold the ejector in inactive position, and means operable from a point exterior the casing for bodily moving the ejector against the tension of said spring, the casing being formed with a dispensing opening for the hairpins, and the cam being adapted to move the ejector out of engagement with a hairpin after an active movement of the ejection 55 in a direction outwardly of the casing.
